United States Patent Office

Des. 198,889
Patented Aug. 11, 1964

198,889

BIN DISPENSER

Simon Heselov, 52 E. Myrtle Ave., Youngstown, Ohio

Filed May 24, 1963, Ser. No. 75,057

Term of patent 14 years

(Cl. D80—9)

I claim:

The ornamental design for a bin dispenser, as shown.
